SLUB DETECTOR

John L. Bitter and Karl Baumert, Elizabethton,
Tenn., assignors to North American Rayon Cor-
poration, New York, N. Y., a corporation of
Delaware

Application May 24, 1933, Serial No. 672,637

1 Claim. (Cl. 28—64)

This invention relates to slub catchers for winding machines and the like but primarily has for its object to devise a simple and effective means whereby the slubs in threads may be dis-
covered.

Another object of the present invention is to devise a simple and positive stopping means for winding machines when a slub or knot is dis-
covered in the thread.

10 A further object of the present invention is to devise a slub catcher which can be quickly and easily adjusted for threads of different thick-
nesses.

15 Still another object of the present invention is to devise a slub catcher which is readily adjust-
able so that a minimum tension will set it into operation.

20 These and other objects will in part become obvious and in part be pointed out in the following specification taken in conjunction with the attached drawings, in which:

Figure 1 is a front elevation of one unit of a winding machine with our invention attached and the machine in running operation;

25 Figure 2 is an enlarged front elevation, parts being broken away and the cone removed, of the upper portion of a winding machine with our invention attached and the parts shown in braking position in full lines after having been
30 released by our invention, the dotted lined posi-
tions are the same as shown in Figure 1;

Figure 3 is a detail perspective view, the slub
35 catcher detector element per se, the lower end
of the actuating lever being shown in dotted
line in position;

Figure 4 is a side elevation of the slub catcher per se with the actuating lever shown in dotted lines; and

Figure 5 is a detail horizontal section on the
40 line 5—5 of Figure 4.

In the winding of threads an important part
45 of the total production now leaves the plant of
the thread manufacturer in packages which
can be used immediately on the knitting ma-
chine, in the shuttle as filling, or in the warping
mill to make warps for the loom. In view of the
above the necessity arises for ensuring a yarn
in which the slubs are positioned in such a
manner as to eliminate the chances of tangling
50 the yarn layer, thereby causing damage to the
fabrics which are being knitted or woven.

It is generally the practice in withdrawing
threads from the yarn packages to do so verti-
cally and should there be any slubs, the ten-
55 dency is for the withdrawn thread to catch on

these slubs with the usual result of either break-
ing the thread or disturbing other yarn layers
which would cause an entanglement and a stop-
ping of the loom or knitting machine. It is
therefore the purpose of the slub catcher or de-
tector to automatically stop the winding ma-
chine during the production of the yarn package
so that the operator may rebreak the thread
and tie a new knot and place this knot where
it will do no harm which is across the end of the
yarn package, thereby preventing the knot from
interfering with the rest of the yarn body.

Heretofore, the slub catchers in general use
have proven unreliable in that the slubs even-
tually worked their way through the slub catch-
ing means and the result was that a number of
undetected slubs got by the operator and into
the yarn package. It was to overcome this fault
that we have invented the attachment which is
the subject matter of the present application.

In the drawings in which like numerals of
reference indicate like parts, 1 indicates the
frame of a winding machine, 2 the header frame
in which is pivoted the traverse thread guide
frame 3. The traverse frame 3 carries the usual
traverse thread guiding means 4 which carries
the button guide 5 by means of which the thread
is laid in the desired cross wind on the take-up
cone 6. The type of winding machine illus-
trated here is used in the winding of cones. The
yarn body is indicated at 7 and the supply spool
at 8.

The thread 9 is drawn from the supply spool
8 through thread guides 10—10, then over the
usual yarn lubricating roller 11. It then passes
25 to another thread guide 12 and is drawn up
through the thread guide 13 which is carried
by the back plate 14 of my slub catcher. The
thread is then drawn through the hinged slub
detector element 15 to the tensioning means 16
which is of the usual construction. After leav-
ing the tension device 16, it passes around a
guide rod 17 and under the projecting arm 18
of the bell crank stopping lever 19 which is
pivoted on the traverse frame dog 20. The
tension of the thread is sufficient to hold this
stopping lever 19 in the position illustrated in
Figure 1 of the drawings or as shown in dotted
lines in Figure 2. After leaving the arm 18,
the thread is carried over the thread guiding
means 4 and through the button guide 5 onto the
take-up cone 6. With the exception of the parts
positioned on the back plate 14 of our device,
and the actuating lever 21, the rest of the con-
struction is usual in the art.

Our invention comprises the device shown in Figure 3 of the drawings, and the pivoted actuating lever 21 which is pivoted on the bracket 22 to which is secured the tension or washboard device 16. The back plate 14 has a hinge bracket 23 to which is hinged the detector element 15. This detector element need not necessarily be pivoted as shown in the drawings, but might be very easily adapted to be slideable in a slotted bracket, whereby when the stub caught in the thread passage would raise the detector element out of the path of the actuating lever, thereby releasing it in a like manner as when hinged as shown in the preferred form of the invention. A hinge pin 24 is fixed to move with the detector element 15 and extends out at one side and back at right angles as shown at 25 so as to project into the path of the enlarged contact end 26 of the actuating lever 21 for a reason later to be more fully disclosed. The detector element 15 has a slot 27 through which the thread 9 passes but in order to allow for the different diameter threads that may be used, two adjustable slides 28-28 are secured to the under side of the detector element 15 and are held in spaced relation by screws 29-29. The plates 28-28 have slots 30-30 through which the screws 29-29 pass and it is readily seen how by loosening the screws 29-29, the plates 28-28 may be moved either toward one another or away thereby decreasing or increasing the passage 31 through which the thread 9 passes. The thread guide 13 which is adjustably mounted on the back plate 14 as shown at 32, centers the thread 9 so that it will pass between the spaced plates 28-28.

To adjust the detector element so that a minimum amount of pull will lift it out of the path of the contact end 26 of the actuating lever 21, there is placed a bracket 33 and a set screw 34 under the detector element 15. A lock nut 35 is also provided, so that when an adjustment is made it will stay in position.

The actuating lever 21 as before mentioned, is pivoted at 36 on the bracket arm 22. It is spring held at 37. The spring 37 is attached to a bracket 38 on the back plate 14 and always tends to pull the lever 21 against the arm 25 of the hinge pin 24.

The upper portion of the actuating lever 21 has a projecting finger 39 which contacts with an arm 40 of the bell crank lever 19 for the purpose of forcing it downwardly when released by the arm 25 of the hinge pin 24. By so doing it forces the other arm 41 of the bell crank lever 19 against the rotating stopping lever wheel 42 which will kick the traverse frame dog 20, pivoted at 53, up, thereby releasing the brake lever 43 which has a lug 44 which had been held in position by the slotted finger 45 of the dog 20.

The starting lever handle 46 and the brake lever 43 are integral one with the other so that

when the handle 46 is moved back again the lever 43 is moved back into engagement with the slotted fingers 45 of the dog 20.

A brake 47 is pivoted at 48 to the brake lever 43 in the usual manner and is forced down into braking engagement with the brake disc 49 in the usual manner when the brake lever is released thereby stopping the take-up spindle 51 of the machine.

In operation the parts are in the position illustrated in Figure 1 of the drawings and as shown in dotted lines in Figure 2. The thread 9 is being drawn from the supply spool 8 and passing through the thread guides 10-10 and over the lubricating roller 11 and through the thread guide 12 in the usual manner. Then through the thread guide 13 and the thread passage 31. Should a stub in the thread attempt to pass through the thread passage 31, the stub detector element 15 would be drawn up as shown in dotted lines in Figure 4 which would depress the arm 25 of the hinge pin 24 and allow the contact end 26 of the actuating lever 21 to be released because of the pull of the spring 37. The actuating lever 21 through the medium of its contact finger 39 pivots the bell crank stopping lever 19 so that the arm 41 is forced against the rotating stopping lever wheel 42 which thereupon kicks the traverse frame dog 20 up thereby releasing the brake lever 43 which is pivoted at 52 and throws the brake 47 into braking engagement with the brake disc 48 thereby stopping the take-up of the thread and enabling the operator to remove the stub and place a knot in a position so that it will not interfere with the drawing off of the thread from the yarn package when it is used on the weaving or knitting machines. In Figure 2 in full lines is shown the position of the parts when released by the stub detector 14 or in other words in the braking position.

From the foregoing description, taken in connection with the accompanying drawings, it is thought the complete construction, operation and advantages of our invention will be clear to those skilled in the art to which it relates.

What we claim is:

Slub detector mechanism comprising a back plate, a hinge bracket on said plate, a detector element pivoted on said hinge bracket, a hinge pin integrally attached to said detector element but pivoting freely in said hinge bracket, said hinge pin being extended to form an abutment for an actuating lever, said actuating lever having means attached thereto tending to force said actuating lever against said extended abutment, said actuating lever adapted to operate a stop mechanism on machines.

JOHN L. BITTER.

KARL BAUMERT.
